DESIGN FOR A PLANTER LAMP

John E. Everett, Evanston, Ill., assignor to
Herman Kravitz, Chicago, Ill.

Application June 3, 1948, Serial No. 146,736

Term of patent 3½ years

(Cl. D48—20)

To all whom it may concern:

Be it known that I, John E. Everett, a citizen of the United States of America, residing at 811 Hinman Avenue, Evanston, in the county of Cook and State of Illinois, have invented a new, original, and ornamental Design for a Planter Lamp, of which the following is a specification, reference being had to the accompanying drawings, forming a part thereof, wherein:

Fig. 1 is a front elevational view illustrating my new design;

Fig. 2, a side elevation;

Fig. 3, a side elevation taken from the side opposite that of Fig. 2;

Fig. 4, a top plan view, and

Fig. 5, a rear elevational view.

The characteristic features of my design reside in the portions shown in the drawing by means of full lines, the broken line indication of plant life being for illustrative purposes only.

I claim:

The ornamental design for a planter lamp, as shown and described.

JOHN E. EVERETT.
